UNITED STATES PATENT OFFICE.

JOHN EDWARD THORNTON, OF WEST HAMPSTEAD, LONDON, ENGLAND, ASSIGNOR TO
JOHN OWDEN O'BRIEN, OF MANCHESTER, ENGLAND.

PAPER FOR PRODUCING PHOTOGRAPHIC PRINTS IN COLORS.

1,263,962.

Specification of Letters Patent. Patented Apr. 23, 1918.

Application filed May 24, 1915. Serial No. 30,171.

To all whom it may concern:

Be it known that I, JOHN EDWARD THORNTON, a British subject, residing at West Hampstead, London, England, have invented certain new and useful Improvements in Paper for Producing Photographic Prints in Colors, of which the following is a specification.

This invention relates to color photography and its object is to provide means whereby prints may be made in natural colors on paper (or other desired surface) for viewing by reflected light, and printed direct from any type of natural color negative, such as the well-known Lumiere autochrome or other form of screen-type transparency.

Many attempts have been made to produce a satisfactory and simple means of obtaining color prints on paper from color screen negatives. For instance the well-known process of Dr. Smith uses a paper coated with dyed gelatins that are printed by the light bleaching out portions of the dyed film according to the filtering effect of the colored negative. Another method, known as the superimposed, uses three prints, one above the other, either by triple sensitizing and triple printing, or by cementing three differently colored section prints in contact 25 with each other. Another method uses a paper having a highly reflective surface, such as a metal coated surface, then a sensitive gelatino-silver layer exposed and developed thereon printed from a selective 30 color-screen negative, and finally covered by a color screen cemented thereto through which the print is seen. All these methods are useful and interesting, but they do not quite satisfy the requirements of present day 35 photographers, and the present invention seeks to provide a process that will.

The invention will be described in connection with the accompanying drawing, where-in—

45 Figure 1 represents a sheet of photographic paper prepared in accordance with the present invention and having colored dots.

Fig. 2 represents a prepared sheet of paper with colored lines, and

50 Figs. 3 and 4 represent a prepared sheet of paper having dots formed by crossed colored lines.

The present invention consists essentially 55 in preparing the paper or other material 1

to be printed upon with a printing surface of extremely fine sub-divisions or dots of sensitized colored gelatin or other suitable colloid in any desired number of colors—say two, three, four or even more—the dots being round, square, hexagonal, or other regular or irregular shapes, as indicated at 2 in Fig. 1 or formed by crossed lines or of a mosaic pattern or the like, as indicated in Figs. 2, 3 and 4. 60

The colored dots upon the surface of the material are so disposed or intermixed that no two juxtaposed dots are of the same color, where an even mixture is desired. But where a preponderance of one or more colors 70 is desired it may be attained by two dots of one color placed next to one dot of another color.

Any suitable dye may be used for coloring the sensitized emulsion, there being a 75 limited number only of dyes available having the necessary properties. They must be capable of being incorporated with the particular form of colloid adopted. They must not re-act upon the sensitizer used. 80

The sensitizer may be a bichromate salt, such as ammonium, potassium, or sodium bichromate; or it may be a silver salt, such as silver bromid or silver chlorid.

The colloid may be gelatin, fish glue, al- 85 bumen, gum, starch, or a mixture thereof.

I prefer, however, to use gelatin, with which is incorporated, before coating, a dye or dyes of a type that will not render the gelatin insoluble, yet capable of being mordanted by the bichromate or else being self-mordanting and requiring no addition. The mordant is necessary in order to prevent the dye washing out from its suspending colloid during the various operations. 90

The bichromate sensitizer may be mixed with the dye and colloid before coating, in which case the paper must be used soon after manufacture. But for a commercial product intended to be kept an indefinite 100 time before use, the bichromate sensitizer is omitted at time of manufacture, and the photographer sensitizes the colored sheet immediately before use in the same way that ordinary carbon tissue is sensitized, by immersion in a bath of bichromate, followed by drying, then printing. 105

To produce prints, the prepared paper is placed in a printing frame face to face in contact with a colored negative of the 110

- screen-plate type, exposed to daylight, electric arc light, or mercury vapor lamps for the requisite time, then developed in hot water if the colloid be gelatin, or in cold water if it be fish glue, albumen, or gum. Development is made from the back, after transfer to a support as in the carbon process.
- The finished result is a picture in colored dots, the shadows of the negative being represented by a greater or lesser number of insoluble colored dots, the half-tones by insoluble dots of lesser height, and therefore less intensity, while the high lights are represented by clear paper owing to the dots thereon remaining soluble and washing off during development. The colors of the dots rendered insoluble by light are defined by the filtering action of the colored dots of the negative.
- 20 Where a quicker printing process is required silver is used instead of bichromate as the sensitizer. In this case a sensitized emulsion of the usual type is used, that is to say one comprising gelatin and silver bromide, or silver chlorid, or a mixture of both. With such emulsion the dyes are incorporated as before, and the mixture applied to paper in fine sub-division in dots or other design in the manner already described.
- 30 After exposure under a colored negative the image is developed by metol, hydroquinone, glycin, or other non-staining developer; then fixed in sodium thiosulfate; then soaked in a bath of bichromate and alum or other suitable oxidizing solution that is capable of rendering the gelatin insoluble in direct proportion to the amount of metallic silver left in the image, and at the same time bleaching the silver; and finally
- 40 developed from the back with hot water to dissolve away the unhardened parts of the gelatin, thus leaving an image in dots of colored gelatin as in the method already described. But when using this silver method the hot water development may be omitted if desired, because the superfluous gelatin has already been rendered transparent by the bleaching action of the bichromate oxidizing bath upon the reduced silver.
- 50 The dots of dyed gelatin or other colloid are applied to the paper by a machine capable of printing or otherwise depositing the colored gelatin dots in such a way that the different colors are correctly interspaced and are not deposited on top of each other.

Instead of colored dots, as shown in Fig. 1, alternating colored lines 3 may be used, as shown in Fig. 2. If it is desired to avoid the necessity for accurate register the colored colloid is applied to the paper in the form of lines that are crossed to produce either square or diamond shaped dots, as indicated at 4 and 5, respectively, Figs. 3 and 4.

60 Where two or more colors overlap one an-

other in either method such will have the effect of introducing black or rather a dark color approaching black which will have the advantage of helping better to define the image.

70 Another method of applying the colored colloid when three colors are required is to first coat the paper all over with plain gelatin, then print the first two colors in lines or dots of red and green, in self-mordanting dyes, such as chrome-dyes, and then to fill in the spaces between by blue dye that will soak into the plain gelatin but not into the printed and mordanted parts.

75 A suitable degree of fineness of all these dots or lines is about 200 to the inch or 40,000 to the square inch.

80 A paper such as described is suitable for producing positives, in colors by direct printing from negatives in colors, such negatives being made by any known system. If the negatives be of the type composed of colored dots, it is desirable to insure best results, that the number of dots per square inch should be greater or less on the positive 85 paper than on the negative from which it is printed, to reduce the number of chance superimpositions of same colors.

90 What I claim as my invention and desire to protect by Letters Patent is:—

95 1. A chromatic printing paper for producing positives in colors by direct printing from negatives in colors, such paper being prepared with a printing surface of colloids in a plurality of colors, finely sub-divided and disposed side by side, the colloids thus 100 presenting a plurality of distinct colors, closely adjacent to one another and in very close formation.

105 2. A chromatic printing paper for producing positives in colors by direct printing from negatives in colors, such paper being prepared with a printing surface of sensitized colloids in a plurality of colors, finely sub-divided and disposed side by side, the 110 colloids thus presenting a plurality of distinct colors, closely adjacent to one another and in very close formation.

115 3. A chromatic printing paper for producing positives in colors by direct printing from negatives in colors, such paper being prepared with a printing surface of sensitized colloids in a plurality of colors, finely sub-divided into dots disposed side by side, the colloids thus presenting a plurality of 120 distinct colors, closely adjacent to one another and in very close formation.

125 4. A chromatic printing paper for producing positives in colors by direct printing from negatives in colors, such paper being prepared with a printing surface comprising a plurality of exceedingly fine dots of colloids in a plurality of colors, disposed side by side in very close formation.

130 5. A chromatic printing paper for pro-

ducing positives in colors by direct printing from negatives in colors, such paper being prepared with a printing surface of colloids in a plurality of colors, the colloid of each 5 color being finely sub-divided and disposed side by side, closely adjacent to one another, and the colloid of one color overlapping the colloid of another color.

6. A chromatic printing paper for producing positives in colors by direct printing from negatives in colors, such paper being prepared with a printing surface of sensitized colloids in a plurality of colors, the colloids of each color being finely sub-divided and disposed side by side, closely adjacent to one another, and the colloid of 15 one color overlapping the colloid of another color.

7. A chromatic printing paper for producing positives in colors by direct printing from negatives in colors, such paper being prepared with a printing surface of colloids in a plurality of colors, the colloid of each color being finely sub-divided 20 and disposed side by side, and the colloids of different colors crossing one another.

8. A chromatic printing paper for producing positives in colors by direct printing

from negatives in colors, such paper being prepared with a printing surface of sensitized 30 colloids in a plurality of colors, the colloid of each color being finely sub-divided and disposed side by side, and the colloids of different colors crossing one another.

9. A chromatic printing paper, capable of producing from a colored negative a positive in colors, such paper having a surface comprising a finely sub-divided colloid in different colors, disposed in juxtaposition to 40 one another, to present to the eye of an observer, a positive picture with full tones, half tones, and high lights which appear to present unbroken continuous tones of various colors, but which in reality consist of a 45 conglomeration of detached or broken points or lines arranged in very close formation, and arranged according to the pattern of the color negative.

In testimony whereof I have hereunto set 50 my hand in presence of two subscribing witnesses.

JOHN EDWARD THORNTON.
